HAIR DRIER

Dwight C. Hudson, deceased, late of Chicago, Ill.,
by Eleanor C. Hudson, administratrix, Chicago,
Ill.

Application April 17, 1937, Serial No. 137,543

4 Claims. (Cl. 34—26)

The primary object of this invention is to improve the operating characteristics of swirl, recirculating hair driers in a manner which not only increases the efficiency of the drier, but also adds greatly to the comfort of the patron.

Further and other objects will become apparent as the disclosure proceeds and the description is read in conjunction with the accompanying drawing, in which

Fig. 1 is a diagrammatic view which will be used in explaining the theory which is believed to underlie the present invention;

Fig. 2 is a sectional view of a preferred form of the invention, the section being taken on the line 2—2 of Fig. 3; and

Fig. 3 is a sectional view taken on the line 3—3 of Fig. 2 looking in the direction of the arrows.

It should be understood that the illustration and description of the preferred form of the invention are for the purpose of complying with Sec. 4888 of the Revised Statutes, and should not be construed as imposing limitations on the appended claims unless required by the prior art.

Experience has shown that the most efficient hair driers depend upon a combination of air circulation, heaters and static pressure to accomplish their intended object. The present invention utilizes all three factors but achieves even greater efficiency in a new and novel manner.

The drier comprises an ovate shell generally designated 10 consisting of a back shell or hood 11 and a front shell or rim 12, the two parts being united by a band 13 welded to the rim 12 and secured to the back hood 11 by screws such as indicated at 14. Both the back and the front shells 11 and 12 are preferably spun in sheet steel and the latter has a large opening 15 adapted to receive the patron's head. The margin of the opening 15 is spun inwardly to give the shell a finished appearance.

A motor pan assembly, generally designated 16, is adapted to be fitted within the back hood 11 before the front hood 12 is secured in place, the assembly comprising a brushless induction motor 17, a single inlet centrifugal fan 18, a pair of heaters 19 and the necessary supporting and screening elements.

The main supporting element consists of a pan 20 having an axial opening 21 through which the shaft 22 of the motor 17 extends, the motor being supported in position on the pan by a plurality of bolts 23 which extend through the motor frame and the pan and receive nuts 24 and 25 between which rubber grommets 26 are

compressed. The motor frame is spaced from the fan by spacer sleeves 27 which bear on the frame and on the nuts 25.

The extended shaft 22 of the motor 17 is secured to the enlarged hub 28 of the fan 18 as by a set screw 29. The fan is normally driven in a clockwise direction when viewed from the opening 15 so that air taken in through the axial inlet 30 is forced out between the blades 31 of the fan in a swirl, the direction of which is indicated by the arrows in Figs. 1 and 2. Dotted arrows have been used to indicate the movement of air above the sectional plane of the drawing and full arrows have been used to indicate the movement of air below the sectional plane.

Adjacent to the mouth of the motor pan 20 are a plurality of right angle brackets 32, each of which has a leg welded to the motor pan and another leg extending inwardly to support a flat ring 33 secured to it by screws 34. A screen 35 is supported on the ring 33 with the aid of metal straps 36 which are welded to the ring, these straps also being used to support heater elements 37 and 38, positioned on opposite sides of the hub 28 of the fan 18.

The leads and electrical circuit for the heaters 37 and 38, motor 17, etc., are not shown as they do not constitute a part of the present invention.

The motor pan assembly 16 is detachably held in place within the back shell 11 by a plurality of screws 39, some of which pass through the supporting swivel 40.

By removing the front rim 12 and the screws 39, the motor pan assembly may readily be removed from the hood.

A plurality of air returners or deflectors 41 are interiorly mounted within the rim 12 at a reclining angle with respect to the direction of the air stream. In other words, the deflectors are mounted so as to form an acute angle on the far side (with respect to the direction of movement of the air stream) of the plane which passes through the axis of the shell and the lower edge of the deflector, as indicated at 42 in Fig. 1. The exact angle for any particular drier will depend upon considerations which will hereinafter appear.

The deflectors 41 are preferably stamped from sheet steel, or formed of other suitable material, and have flanges 43 and 44 which are adapted to be welded to the front hood 12. The inner edges of the deflectors are turned over as indicated at 45 in order to obtain a smooth edge, and the upper edges of the deflectors are beveled off as indi-

cated at 46 in order to allow the swirling air to impinge upon the various deflectors.

It is realized that vanes have heretofore been used with faces coincident with axial planes for the purpose of building up a static pressure within the drier, but the descending air stream in striking the vanes is deflected outwardly, thus causing a certain amount of discomfort to the patron in having warm air blown over the patron's face.

In the drier of the present invention, the deflectors or air returners 41 are not used for the purpose of building up static pressure, and, as a matter of fact, do not accomplish that function, but rather to effect a substantially complete recirculation of the air within the drier.

The theory of operation for this drier may best be understood by referring to Figs. 1 and 2. Assuming the drier in operation, air is forced outwardly through the blades 31 of the fan 18 to produce an air stream which swirls around the shell and slowly descends in somewhat the path indicated by the dotted and full line arrows. A certain quantity of fresh air is drawn into the air stream through openings 47 in the rear of the back hood 11, the air first passing over the motor 17 and then entering into the air stream through the motor pan opening 21. The fan 18 is of such capacity that it in itself is capable of producing static pressure within the shell without any reference to the resistance to air flow of the deflectors 41. Preferably the width of the fan, i. e., the width of the blade is from 20% to 40% of the diameter of the fan as this relationship in conjunction with the shape and size of the shell, enables the fan to produce not only a static pressure within the shell, but also a violent turbulence or air stream velocity which contributes greatly to the speed at which hair may be dried. For the ordinary drier, a fan having a diameter of 8 inches and blade width of 2 inches has been found very satisfactory, and, of course, the inlet opening should be as large as possible for best efficiency.

Since the swirling air stream indicated by the arrows in Figs. 1 and 2 has a downward component, it is obvious that when vanes are placed in axial planes, the air stream strikes the vanes at an angle which causes the air to be deflected outwardly thus causing not only an undesirable loss of heated air, but also discomfort to the patron. By slanting the deflectors so that the air stream in striking them is deflected inwardly toward the air inlet of the fan, substantially complete recirculation of the air is obtained and only that amount of air which is required for insuring proper ventilation of the motor 17 is expelled through the mouth of the hood. The air expelled, however, is not reflected air, but air which is forced out by static pressure so that its velocity is considerably lower than the air that is forced out when vanes are used in axial planes.

In practice, the deflectors 41 are set at an angle of approximately 70° with the plane normal to the longitudinal axis of the drier, or, in other words, the angle 42 of Fig. 1 (it being understood that this is only a diagrammatic view) is approximately 20° but these angles may

be varied within fairly wide limits, particularly in increasing the angle 42.

It will be observed that when the deflectors are set at an angle somewhat as shown in the drawing, the air is deflected in lines substantially parallel to the axis of the drier to the inlet of the fan 18.

Obviously, a deflector placed substantially at right angles to the descending air stream would accomplish, to a somewhat lesser degree, the desired result inasmuch as there is a low pressure area created by the fan along the axis of the drier which naturally draws the air inwardly unless given a definite component of movement outwardly, as is the case where the vanes are placed in planes which are coincident with the longitudinal axis of the drier.

A few dimensions are indicated on the drawing to show desirable relationships between the size of the hood, fan size, angle of deflectors, etc., but these should not be construed as limiting in character.

Experience has shown that hair may be dried in nearly half the time that is required for driers now on the market.

What is claimed is:

1. In a hair drier, a shell having an opening at one end, means for circulating air in the shell so that it takes a spiral path in travelling lengthwise of the shell toward the opening, and means for minimizing air leakage at the opening including deflectors placed radially adjacent to the opening and set at a reclining angle to the longitudinal axis of the shell.

2. In a hair drier, a shell having an opening at one end, means for circulating air in the shell so that it takes a spiral path in travelling lengthwise of the shell toward the opening, and means for minimizing air leakage at the opening including deflectors placed radially adjacent to the opening and set at such an angle with respect to the air stream that the greater part of the air in the stream is returned to the air circulating means.

3. In a hair drier, a shell having an opening at one end, means for circulating air in the shell so that it takes a spiral path in travelling lengthwise of the shell toward the opening, and means for minimizing air leakage at the opening including deflectors placed radially adjacent to the opening and set at such an angle with respect to the air stream that the greater part of the air in the stream is deflected upwardly along the axis of the shell to the air circulating means.

4. In a hair drier, a shell having an opening at one end, means for circulating air in the shell so that it takes a spiral path in travelling lengthwise of the shell toward the opening, and means for minimizing air leakage at the opening including deflectors placed radially adjacent to the opening and set at such an angle with respect to the air stream that the air is deflected back into the shell as distinguished from being deflected outwardly from the shell.

ELEANOR C. HUDSON,
Administratrix of the Estate of Dwight C. Hudson, Deceased.
